(57) CLAIM

The ornamental design for a basketball bottle, as shown and described.

DESCRIPTION

FIG. 1 is a perspective view of a basketball bottle showing my new design.

FIG. 2 is a left, side view thereof, wherein the right, side view is identical to the left, side view.

FIG. 3 is front view thereof, wherein the rear view is identical to the front view.

FIG. 4 is a top view thereof; and,

FIG. 5 is a bottom view thereof.

The broken lines shown in the drawings depict portions of the basketball bottle that form no part of the claimed design.
